TRANSPORTATION TICKET OR OTHER
PAPER

George C. Wehmann, Jr., New Richmond, Ohio

Application August 1, 1941, Serial No. 405,051

2 Claims. (Cl. 282—12)

This invention relates to a ticket, bill, commercial paper, or the like comprising at least two sections, generally similar in form, but provided with different data, and in which only one section of the paper at a time is adapted to be removed as a unit of service, transportation or other subject matter to which the paper may apertain, is performed or completed.

An object of the invention is to provide such a paper in which the various units of the service or transportation may be filled out on the uppermost or outside section of the paper, while the underlying remaining sections of the paper are at the same time provided at the time of the original filling out, and by virtue of the duplicating means herein provided, with single units of the subject matter involved, each differing from the units on the other underlying sections of the paper.

Another object is to obviate, in tickets and other papers here in question, the repetition of data that must be inserted, according to present practices, on each section of the paper involved.

Another object is to produce commercial papers, tickets and the like in more convenient and cheaper form.

These and other objects are attained by the means described herein and illustrated in the accompanying drawing, in which:

Fig. 1 is a perspective view of the present invention as applied to a ticket for bus transportation, the ticket being partially opened out to show various parts.

Fig. 2 is an opened out plan view of the ticket, showing that face on which the totality of data is originally inscribed.

Fig. 3 is a view similar to Fig. 2, showing the opposite side of the paper or ticket.

As already intimated, the present invention is not in any way limited to the particular form of paper disclosed herein but is useful in various businesses and professions in any kind of transaction in which the individual to whom service is rendered is provided with a paper formed of detachable sections and adapted to be removed one at a time as units of service are completed.

It is convenient, however, to illustrate the invention as applied to a bus ticket. In transportation of this kind, it is common for the traveler to be routed over various lines, belonging to different companies, in which case the ticket must indicate the various units of travel and the individual bus lines serving each of the units involved. According to the present prac-

tice, a ticket, of greater or lesser length depending upon the length of the trip involved, is made out at the issuing office, it being necessary to insert a considerable amount of data upon each of the sections forming the ticket. As a new unit of the trip is begun, the traveler presents his ticket and the proper section is torn off by the operator. The work involved in filling out a ticket of this kind and the time incident thereto are considerable items which are obviated by means of the present invention.

The latter, briefly, provides for a ticket, preferably formed in parallel folds, each fold being provided with carbon or duplicating material in predetermined portions on its back or rear face so that, when the topmost of the sections is filled out, each section of the ticket will show a different unit of the trip, of which the totality of units is indicated on the topmost section. The various sections of the ticket are, of course, removable and are taken up by the operator upon presentation by the traveler, as each unit of the trip is completed and another begun.

In greater detail and with reference to the drawing:

The ticket may be formed of suitable paper, preferably thin and strong in character, and this paper is folded in parallel sections, as shown in Fig. 1, resulting in a top section 5, connected by a scored or perforated line 6, to a second section 7, the latter being connected along the line 8 to a third section 9. Similarly, the section 10 is connected to the section 9 along the scored or perforate line 11. It is obvious that the number of sections may be greater or less, but the invention will be apparent from the structure shown. The topmost or outer section 5, as more clearly seen in Fig. 2, may have a top extension 12 connected by a score line 13 with the body of the ticket, the extensions 12 of a number of the tickets being connected together to form a book or the like, and being adapted to be torn off along the perforate line 13. The top section 5 is that which is filled out and retained at the issuing office and hence, in addition to the name of the company, and the usual type of data as indicated adjacent the top of the ticket, the middle and lower portion of the ticket, as seen at the right-hand side of Fig. 2, is filled out with the names of the towns or cities forming units of the trip. For example, on the ticket shown, the trip begins at Cincinnati and the first unit of the trip will be completed at Dayton, the transportation being provided by the bus line indicated by the letters "KBL," which letters and similar indicia of other companies

are placed underneath the heading "Via.". The second unit of the trip is completed at Toledo and the transportation is provided by the line indicated by the letters "C & LE." The third and last unit of the trip terminates at Detroit, the final destination, and the transportation for this unit is provided by the bus line indicated by "GL."

It may be explained here that the designation "Origin Miami, Fla.", as seen on the ticket in Fig. 2, indicates that a traveler coming from Miami, Florida, has had his ticket reissued at Cincinnati to provide for remaining units of the journey. It is apparent that whether the ticket is an original or reissued ticket makes no difference so far as the invention is concerned. Below the indication of origin the final destination as well as the fare are indicated, which data is reproduced and shown on all sections of the ticket. The bottom tab 14 on section 5 of the ticket may be printed with suitable instructions for filling out the ticket.

With reference now to Fig. 3, the present invention provides for the rear face of section 5 having attached thereto or formed thereon a small carbon or duplicating area 15 and a large area 16. The area 15, when the sections of the ticket are folded one upon the other, is disposed against the small squares 17 (Figs. 1 and 2) in which squares a check mark is made for indicating whether the ticket is a reissue, a round trip, one-way, etc.

The larger area 16 on the rear of ticket section 5 is so disposed and of such extent as to reproduce on the face of the underlying ticket section 7 only the names of the two cities forming the last unit of the trip, that is to say, the section 7 of the ticket would carry the traveler from Toledo to Detroit. The origin Miami and destination Detroit indicia are again reproduced on this as well as on the underlying sections of the ticket.

Similarly, the section 7 is provided on the rear with an upper carbon area 19 corresponding to the top area 15 of the preceding ticket section and a lower area 20 for the origin and destination indicia. The central area 21, however, of the carbon material is of such extent and so positioned as to reproduce on the underlying section 9 of the ticket, as seen in Fig. 2, the unit of the trip from Dayton to Toledo. This section 9 of the ticket, in turn, is on its rear face, as shown in Fig. 3, provided with a carbon area 23 of such extent as to reproduce, on the underlying or last section 10 of the ticket, the unit of travel, Cincinnati to Dayton. It will be seen that the last two sections 9 and 10 of the ticket may be of shorter length than the preceding sections since they need not contain as much data as the first two sections. The bottoms of sections 7, 9 and 10 of the ticket may be attached to the body of the respective ticket sections by score line and may be adapted to be filled in with data forming additional passenger identification or the like. One of these tabs is indicated at the bottom of section 9 in Fig. 2 where the words "Auditor's

advice" appear. These tabs are commonly known as "hat checks."

It should be observed that the trip-indicating carbon areas on sections 5 and 7 are formed with small blank portions 24 (Figs. 2 and 3) so that there will be indicated on the underlying ticket section, only that bus line which is engaged to perform the service for that unit of the trip.

In use, the top section of the ticket 5, after it has been properly filled out with all the required data, is torn off and retained for record at the issuing office. The operator of the bus carrying the passenger for the first unit of the trip removes the section of the ticket designated for the first unit of the trip which, as here illustrated, is the last of the fold sections, namely, section 10. After this unit of the trip is completed, the operator who carries the passenger for the next unit, tears off section 9, and the third operator at the beginning of the last unit of the trip takes up the final section of the ticket. The issuing office thus knows what line is responsible for each unit of the trip and the various billing and other transactions between the companies involved is greatly facilitated and expedited, and this in addition to the various advantages heretofore discussed as pertaining to the means of this invention.

Various modifications suggest themselves upon consideration of the means herein disclosed but these are believed to be comprised within the scope and spirit of the invention.

What is claimed is:

1. A bus or other transportation ticket comprising a sheet of paper folded in zig-zag fashion to provide a series of overlying sections, the face of one of the outer sections having appropriately designated spaces for indicating thereon in progressive succession the units or stages of a total trip, and areas of duplicating material disposed on the rear of said sections in predetermined relative positions such that each section below said total-trip section will be inscribed with only one unit of the trip, said units being shown on successive sections whereby the latter may be removed in order, as required, during the progress of a trip, said total-trip section being retained at the issuing point, or the like.

2. A bus or other transportation ticket comprising a sheet of paper folded in back-and-forth fashion along parallel tear lines to provide a series of overlying sections, the face of one of the outer sections having appropriately designated spaces for indicating thereon in progressive succession the units or stages of a total trip, and areas of duplicating material disposed on the rear of said sections in predetermined relative positions such that each section below said total-trip section will be inscribed with only one unit of the trip, said units being shown on successive sections whereby the latter may be removed in order, as required, during the progress of a trip, said total-trip section being retained at the issuing point, or the like.
